UNITED STATES PATENT OFFICE.

WILLIAM J. TANGERMAN, OF HAMMOND, INDIANA.

CAR BOLSTER.

1,412,071.

Specification of Letters Patent. Patented Apr. 11, 1922.

Application filed November 28, 1919. Serial No. 341,002.

To all whom it may concern:

Be it known that I, WILLIAM J. TANGERMAN, a citizen of the United States, and a resident of Hammond, Lake County, Indiana, have invented a certain new, useful, and improved Car Bolster, of which the following is a specification.

My invention relates generally to improvements in railroad car bolsters but relates, in some aspects, particularly to bolsters for the under frames of tank cars.

The general object of my invention is to provide a body bolster of simple construction in which the parts shall be so disposed as better to withstand service conditions, and which shall be of such construction that it can be produced from materials of standard forms or construction obtainable in the open market.

It is also an object of my invention to provide a method of producing body bolsters in less time, with less material, at less cost and of greater strength, for the metal employed, than is obtained in methods of production heretofore used; and it is also an object of my invention to provide a method of producing body bolsters whereby standard rolled sheets and shapes may be utilized thus making available a constant supply of materials at relatively low cost.

My invention consists generally in the form, arrangement, construction and co-operation of the parts; and in the steps, acts, and sequence thereof followed in the manufacture of the bolsters, whereby the above named objects, together with others that will appear hereinafter, are attainable, and my invention will be more readily understood by reference to the accompanying drawings which illustrate what I consider, at the present time, to be the best embodiment thereof.

In said drawings:

Fig. 1 is a perspective view of a channel member from which part of the bolster is constructed.

Fig. 2, is a perspective view of another channel member from which another part of the bolster is constructed.

Fig. 3, is a side elevation of the channel members of Fig. 1, being, however, cut into two parts.

Fig. 4, is a side elevation of the channel member of Fig. 2 cut into two parts.

Fig. 5, is a perspective view of a portion

of the channel which is removed for use in another part of the bolster.

Fig. 6, is a perspective view of one end portion of the under frame of a car provided with a body bolster embodying my invention; and

Fig. 7, is a perspective view of one of the end portions of the bolster some of the parts being broken away better to disclose the interior construction.

Fig. 8, is a detail view substantially on the line 8—8 of Fig. 6.

As stated in the opening of the specification it is an object of my invention to produce a body bolster, largely from standard roll sections or shapes, and to do so substantially without waste. As a first step in the method of manufacture, I select a channel member 2 which is a standard rolled section such for example, as a fifteen inch, thirty-three pound section. The length of the channel member 2 is such as to be substantially twice as long as the desired channel section.

As a next step I cut the channel member 2, into two parts as along the double curved dotted line 3, of Fig. 1, thus providing two complementary channel members 4 and 5 which comprise body portions 4' and 5' respectively and tongue portions 4" and 5" respectively. The channel member may be cut or severed in desired or approved manner, as for example, by the use of an oxyacetylene or other torch. The tongue portion it will be noted in each instance embodies therein one of the flanges and a portion of what is termed the web of the channel member. Another channel member of the size of that shown in Fig. 1 is provided which, however, is cut along the double curved dotted line 6 (see Fig. 2) which line of severance, is reversed with respect to the line of severance shown in Figs. 1 and 3. The severed and separated channel members 7 and 8 illustrated in Fig. 4 are thus provided. The channel members 7 and 8 comprise, respectively, body portions 7' and 8' and tongue portions 7" and 8". The tongue portions of the respective channel parts 4, 5, 7 and 8 are severed as along the lines 9, 10, 11 and 12, respectively, thus providing a plurality of small parts 13 of the general form shown in Fig. 5.

The body bolster as a whole consists of

- the channel members 4, 5, 7, and 8, the members 4 and 8 constituting a pair, and the members 5 and 7 constituting a pair. As shown in the perspective view Fig. 6, the 5 parts 4 and 8 are arranged on the near side of the center sill 14, whereas the parts 5 and 7 are on the other side. In positioning the parts the tongue portions 4" and 8" respectively, extend outwardly in a transverse 10 direction from the center sill 14, whereas the body portions 4' and 8' terminate adjacent the center sill. This positioning of the parts causes the flange portions of the channel members to extend in opposite directions 15 or in other words causes the web portions of the channel members to face each other. A similar disposition of the channel members 5 and 7 is made upon the far side of the car.
- 20 The respective channel members are held in spaced relation by means of the upper cover plate 15 which extends the full length of the bolster crossing the center sill and which is secured to the flanges of the bolster 25 parts 4, 5, 7 and 8 by suitable rivets. The cover plate 15 is also secured to the flanges of the center sill channel members 16 and 17 as by riveting. The center sill channels 16 and 17 are also provided with a cover 30 plate 18 secured by riveting to the flange parts thereof. The bolster parts 4, 5, 7 and 8 extend a sufficient distance above the level or top of the plate 18 so that the bolster cover plate 15 may rest thereon, i. e. it is in 35 a plane with the top flanges of the bolster parts. The lower cover plate 19 is also riveted, the bolster parts and lower part of the center sill thereby further assisting in the proper spacing of the bolster parts and very 40 considerably strengthening them. Both the cover plates 15 and 19 are composed of standard plate material procurable in the open market.
- 45 The various channel members 4, 5, 7 and 8 of the bolster are further secured to the channel members of the center sill as by means of four angles one of which is shown in Fig. 6, and which bears the reference character 20. Other angles are similarly 50 positioned, i. e. where body portions of the members 4, 5, 7, and 8 meet the center sill. The bolster channel members are additionally held in proper spaced relation by means of separators, one at each end of the bolster, 55 and which appear in Figs. 6 and 7 bearing the reference character 21. The separator 21 is a channel member which is bent to L-shape, providing the vertical portion 21' and the horizontal portion 21" (see Fig. 7).
- 60 The flange portions 22 and 23 thereof are secured to adjacent parts of the bolster as by means of rivets. The opposite end of the bolster is provided with a similar separating angle member. These members serve 65 not only as separators but they also serve

as lugs for bands or rods which tie the tank to the under frame. For this purpose the hole 25 is provided in the portion 21" of the separator through which the lower end of the tank band passes. The tie band not 70 being strictly a part of the bolster is shown only by means of dotted lines in Fig. 7, and bears the reference character, 26.

At times it is desirable to jack up the under frame and it is convenient to place the 75 jack under the bolster ends. For this reason, I provide the angle jacking members 27 which are made by cutting away a part of the member 13 (see Fig. 5) as along the dotted line 28. They are riveted to the separating member.

The tank supports 29 are shown in certain figures of the drawings, but these will not be described for the reason that they constitute no part of the present invention and are 85 shown only to indicate the adaptability of the bolster to tank car construction.

It is now obvious that in the production of my body bolster practically all of the metal selected is utilized. This elimination 90 of waste reduces very materially the cost of the bolster.

Again it will be noted that castings and special shapes heretofore largely utilized in bolster construction have been supplanted 95 by the use of standard shapes and plates which not only greatly reduce the initial cost of the bolster, and simplify its manufacture, but which also results in a great saving of time when it becomes necessary to repair the 100 car for the reason that the repair parts, i. e. the plates and shapes necessary may be obtained from any warehouse. That is to say, it is not necessary to send to the manufacturer or original car builder for the parts, which is 105 necessarily the case where special castings or pressed shapes are used. Thus the repair of the car is simplified and cheapened and undue delay avoided.

One more point should be mentioned and 110 that is that a bolster is subjected to unusually severe strains, due to the rocking of the car, along those portions joining the vertical and horizontally disposed parts of the bolster. Under prior constructions utilizing 115 channel members formed of pressed plates, the flanges of the channel parts were joined to the base by a rounded portion which in the pressing operation was actually reduced in thickness and thereby weakened at a point 120 where greater strength actually is required than in other parts of the bolster. As a result of this fact, it is not uncommon to find bolsters that are cracked or fractured along that portion. In the rolled shape which I 125 employ the flange is actually reinforced where it joins the base so that the bolster is better adapted to withstand the severe strains, imposed by rocking and other movements of the car in service.

The bolster is further strengthened by the channel member 30 which is interposed between the sill members 16 and 17 where the bolster parts, heretofore described, join the 5 sill members (see Fig. 8).

It is thought that the foregoing description of the method and the resulting structure will be sufficient to teach the advantages to those skilled in the art without further 10 comment, but inasmuch as this disclosure will also suggest to others, modified structures whereby the substantial objects and purposes of my invention may be attained, I do not wish to be limited to the specific 15 construction herein shown and described, nor to the precise steps of the method, nor to the stated sequence thereof, except only as may be necessary by limitations in the hereunto appended claims.

20 I claim:

1. A body bolster embodying therein a plurality of pairs of rolled channel members, one pair arranged on each side of the car center sills, the webs of the channel 25 members facing each other, and means spacing said members apart and securing them to the center sills.

2. A body bolster embodying therein a plurality of pairs of rolled channel members, one pair arranged on each side of the car 30

center sills, the webs of the channel members facing each other, and means spacing said members apart and securing them to the center sills, one of said spacing members being formed and positioned to serve as a tank 35 band lug.

3. A car underframe construction having sills in combination with a body bolster, said bolster comprising two rolled channel members extending from each side of the center 40 sills, separators secured to and holding respective channel members in spaced relation, and means securing said channel members to the center sills, and top and bottom cover plates secured to the bolster and center sill 45 parts.

4. A car underframe construction having center sills in combination with a body bolster comprising spaced channel members secured to the center sill and a top cover 50 plate secured to the flanges of said channels, said channels being reinforced where the flange thereof joins the web portion thus adapting the bolster to withstand the severe strains imposed by rocking movements of 55 the car.

In testimony whereof, I have hereunto set my hand, this 7th day of November, 1919.

WILLIAM J. TANGERMAN.
